US0D1024957S

(12) **United States Design Patent** (10) Patent No.: **US D1,024,957 S**
(45) Date of Patent: ** Apr. 30, 2024

(54) **CHARGER FOR WIRELESS EARBUDS**

(71) Applicant: **LG ELECTRONICS INC.**, Seoul (KR)

(72) Inventors: **Soonhyun Park**, Seoul (KR); **Byunghyun Yi**, Seoul (KR); **Gangho Woo**, Seoul (KR)

(73) Assignee: **LG ELECTRONICS INC.**, Seoul (KR)

(**) Term: **15 Years**

(21) Appl. No.: **35/512,539**

(22) Filed: **Mar. 4, 2021**

(80) **Hague Agreement Data**

Int. Filing Date: **Mar. 4, 2021**
Int. Reg. No.: **DM/213263**
Int. Reg. Date: **Mar. 4, 2021**
Int. Reg. Pub. Date: **Sep. 10, 2021**

(30) **Foreign Application Priority Data**

Oct. 30, 2020 (KR) 30-2020-0052268
(51) **LOC (14) Cl.** **13-02**
(52) **U.S. Cl.**
USPC **D13/108; D3/294**
(58) **Field of Classification Search**
USPC D13/103, 107, 108, 118, 119; D3/201, D3/218, 273, 274, 276, 294, 295; D14/205, 223, 240
CPC . A45C 2011/001; B65D 43/16; H04R 1/1025
